DIALING TOOL

Anthony P. Lynn, Elmhurst, and Gary A. Lynn,
River Grove, Ill.

Application September 3, 1947, Serial No. 771,886

7 Claims. (Cl. 179—90)

1

This invention relates to improvements in dialing tools of the type adapted for use in actuating the rotatable dials provided on automatic telephone instruments. Automatic telephones now in common use are provided with a fixed inner plate bearing numbers and letters, and also with an outer plate adapted to rotate relative to the inner plate, the outer plate being formed with a plurality of finger receiving apertures normally disposed in alignment with their respective numbers and letters provided on the inner plate. In dialing hundreds of numbers per day, it will be appreciated that an operator's finger will become sore or injured and, as a result thereof the operators usually resort to the unauthorized use of pencils, rods, and the like for insertion in the finger apertures, thereby often causing injury to the dialing equipment.

It is an object of the present invention to provide a dialing tool adapted to facilitate the manipulation of telephone dials, and which will not cause injury to the dialing equipment.

It is a further object of this invention to provide a dialing tool embodying a spherical-shaped knob journaled for rotational movement upon the end of an adapter, the adapter being formed with improved means for detachable engagement upon the end of a lead pencil, rod, or the like.

This invention further contemplates the provision of improved means for assembling the spherical knob for rotatable movement upon the end of the adapter, said securing means being confined within the spherical knob to provide a smooth even exterior surface on the knob.

This invention further contemplates the provision of a dialing tool embodying an adapter which is slotted longitudinally to provide a plurality of resilient fingers to receive the end of a lead pencil, or the like, and a locking sleeve for telescopic movement over the resilient fingers to hold the latter in tight frictional engagement against the engaged portion of the lead pencil.

This invention further contemplates the provision of a dialing tool which is relatively simple and inexpensive in construction, reliable in operation, and which will not readily get out of order.

This invention embodies other novel features, details of construction and arrangement of parts which are hereinafter set forth in the specification and claims and illustrated in the accompanying drawing, wherein:

Fig. 1 is a longitudinal sectional view illustrating a dialing tool embodying features of this invention.

2

Fig. 2 is a transverse sectional view taken along the line 2—2 of Fig. 1.

Fig. 3 is a longitudinal sectional view illustrating a modified form of this invention.

5 Fig. 4 is a longitudinal sectional view illustrating another modified form of this invention.

Fig. 5 is a plan view illustrating a telephone dialing device embodying an outer rotatable dial provided with apertures to receive the spherical 10 knob of the dialing tool.

Fig. 6 is an enlarged detail sectional view illustrating the manner of applying the dialing tool in a finger opening of a telephone dial.

Referring now to the drawing for a better 15 understanding of this invention, and more particularly to Figs. 1 and 2 therein, the dialing tool is shown as comprising a spherical-shaped knob 7 formed with a cylindrical bore 8 to receive a cylindrical bearing portion 9 of an adapter 10.

20 The outer end of the adapter 10 is in the form of a cylindrical sleeve 11 formed with longitudinally extending slots 12 to define a plurality of resilient fingers 13 to receive and snugly engage the end of a pencil 14 illustrated in dotted outline. The 25 adapter 10 is provided with a wall 16 at the inner end of the bearing portion 9, the wall being formed with a centrally disposed aperture 17 to receive the threaded end of the screw 18. To insure free rotational movement of the knob 7 about the adapter 10, the bearing portion 9 is provided with an annular bearing surface 21 to coact with the adjacent surface of the cylindrical bore 8.

The dialing tool is adapted for detachable engagement upon the eraser end of a standard lead 35 pencil 14, the pencil being of the type in which an eraser 22 is securely mounted upon the end of the pencil by means of a metallic retaining band 23. It will be noted that the inner diameter of the bearing portion 9 corresponds to the diameter of the eraser 22; and that the inner diameter of the cylindrical sleeve portion 11 corresponds to the outer diameter of the metallic band 23, thus insuring a compact unit of sturdy construction.

45 After the metal band 23 of a pencil has been inserted into the sleeve portion 11 of the adapter, a retaining sleeve 24 is moved axially into position to snugly enclose the resilient fingers 13 and to move the latter into tighter frictional engagement with the metal band 23. When the adapter is thus assembled upon the end of a pencil, it is secured against movement relative thereto, but may readily be removed for attachment to another pencil. During inward movement of the 55 locking sleeve 24, it is brought to rest against an

annular shoulder 26 formed on the adapter. In assembling the knob 7 for rotational movement upon the bearing portion 9 of the adapter 10, the self-threading screw 18 is pressed axially into the recess 19 provided in the knob 7. Self-threading screws of the type illustrated at 18 are well known in the manufacturing art, and are of the type adapted to form threads within a drill hole, thus eliminating a tapping operation.

Referring now more particularly to Figs. 5 and 6, the dialing tool is adapted for use in rotating an outer dial 27 formed with a plurality of finger receiving apertures 28. The outer dial 27 is journaled for rotational movement relative to an inner dial 29 bearing numbers and/or letters 31. In dialing a number, the outer dial 27 is rotated in a clockwise direction until an operator's finger or a dialing tool is brought into contact with a fixed abutment arm 32. As illustrated in Fig. 6, the dialing tool knob 7 is slightly larger in diameter than the diameter of the finger receiving apertures 28 provided in the outer dial 27. During rotational movement of the outer dial 27, it will be noted that the dialing tool knob 7 is free to rotate about the bearing end 9 of the adapter 10, thus preventing wear or injury to the walls defining the finger receiving apertures 28.

Fig. 3 in the drawing illustrates a modified form of this invention in which a spherical-shaped knob 36 is provided with an enlarged diameter bore 37 to receive a bearing portion 38 of an adapter 39. At the inner end of the bore 7 is provided a coaxially disposed bearing ring bore 41 to receive a bearing ring 42. A self-threading rivet 43 extends through the bearing ring 42 for self-threading engagement in a drill hole 44 provided in the end of the bearing portion 38. In assembling the dialing tool, the bearing ring 42 is first assembled in position upon the bearing portion 38 of the adapter 39 by means of the self-threading screw 43. By providing a forced fit for the bearing ring 42 in the bore 41, the knob 36 is assembled upon the adapter 39 by merely forcing the bearing ring into the bore 41. This form of the invention is otherwise similar to the form heretofore described and illustrated in Figs. 1 and 2 of the drawing.

Fig. 4 illustrates another modified form of this invention in which an adapter 46 is provided with a bearing portion 47 having a bearing shank 48 for rotatable engagement in the bearing ring 42 of the spherical-shaped knob 36 which is similar to the knob heretofore described and illustrated in Fig. 3 of the drawing. In assembling this modified form of dialing tool, the bearing ring 42 is first mounted upon the bearing shank 48 and the end of the bearing shank 48 is peened over to provide an annular shoulder 49 to prevent axial displacement of the bearing ring. In assembling the knob 36 upon the adapter 46, the bearing ring 42 is forced into the reduced diameter bore 41. This form of the invention is otherwise similar to the form heretofore described in connection with Fig. 3 of the drawing, except that the adapter is not formed with longitudinally extending slots 12 or provided with a retaining sleeve 24.

In the manufacture of the dialing tool, it is contemplated that the dialing knob, adapter and the locking sleeve may be formed of any suitable material, such as metal or plastic, to provide an adapter for detachable engagement upon the end of a lead pencil, and a spherical-shaped knob journaled for rotational movement relative to the adapter. It will further be noted in each of the forms of this invention that the spherical-

shaped knob is provided with a smooth outer surface, free of indentations or rivet heads, and that the knob is adapted to be simply and inexpensively assembled upon the end of the adapter by telescopic movement of the parts. It is also contemplated that the ends of the rivets or screws 18 and 43 may be provided with knurled surfaces in place of screw threads.

While this invention has been shown in several forms, it is obvious to those skilled in the art that it is not so limited but is susceptible of various changes and modifications without departing from the spirit and scope of the claimed invention.

15. We claim as our invention:

1. In a dialing tool, a substantially cylindrical hollow sleeve-shaped adapter formed with a wall at its inner end and adapted to embrace the outer surface of a handle, a knob provided with an enlarged cylindrical bore and a coaxial reduced diameter bore opening into said enlarged bore and terminating short of the outer surface of said knob, the inner end of said adapter being disposed within the enlarged bore of said knob and embraced by said knob, and means secured in said reduced bore to engage the inner wall of said adapter and prevent axial displacement from its position within said enlarged bore.

2. In a dialing tool, a substantially cylindrical hollow sleeve-shaped adapter formed with a wall at its inner end and adapted to embrace the outer surface of a handle, a knob provided with an enlarged cylindrical bore and a coaxial reduced diameter bore opening into said enlarged bore and terminating short of the outer surface of said knob, whereby said knob surface opposite said enlarged cylindrical bore is continuous, the inner end of said adapter being disposed within the enlarged bore of said knob and embraced by said knob, and means secured in said reduced bore to engage the inner wall of said adapter and prevent axial displacement from its position within said enlarged bore.

3. In a dialing tool, a sleeve-shaped adapter formed with a wall at its inner end, said adapter being formed with a journal surface spaced from the inner end thereof, a spherical-shaped knob having a bore extending inwardly from one side thereof to receive the inner end of said adapter and the journal surface formed thereon, a bearing ring secured within the inner end of the bore provided in said knob, and means provided on the inner end of said adapter to engage said bearing ring to hold the knob and adapter in assembled relatively rotatable engagement.

4. In a dialing tool, a sleeve-shaped adapter formed with a wall at its inner end, said adapter being formed with a journal surface spaced from the inner end thereof, a spherical-shaped knob having a bore extending inwardly from one side thereof to receive the inner end of said adapter and the journal surface formed thereon, a bearing ring secured within the inner end of the bore provided in said knob, means provided on the inner end of said adapter to engage said bearing ring to hold the knob and adapter in assembled relatively rotatable engagement, said means comprising a self-threading screw secured to the inner end of the adapter.

5. In a dialing tool, a sleeve-shaped adapter formed with a wall at its inner end, said adapter being formed with a journal surface spaced from the inner end thereof, a spherical-shaped knob having a bore extending inwardly from one side thereof to receive the inner end of said adapter

and the journal surface formed thereon, a bearing ring secured within the inner end of the bore provided in said knob, means provided on the inner end of said adapter to engage said bearing ring to hold the knob and adapter in assembled relatively rotatable engagement, said means comprising an upset shoulder formed on the inner end of the adapter for engagement against the inner side of said bearing ring.

6. In a dialing tool, a sleeve-shaped adapter formed with a wall at its inner end, said adapter being formed with a journal surface spaced from the inner end thereof, a spherical-shaped knob having a bore extending inwardly from one side thereof to receive the inner end of said adapter and the journal surface formed thereon, a bearing ring secured within the inner end of the bore provided in said knob, means provided on the inner end of said adapter to engage said bearing ring to hold the knob and adapter in assembled relatively rotatable engagement, the outer end of said adapter being formed with longitudinally extending slots to provide a plurality of resilient fingers, and a locking sleeve to receive and snugly enclose said locking fingers.

7. In a dialing tool, a sleeve-shaped adapter formed with a wall at its inner end, said adapter being formed with a journal surface spaced from the inner end thereof, a spherical-shaped knob having a bore extending inwardly from one side thereof to receive the inner end of said adapter

and the journal surface formed thereon, a bearing ring secured within the inner end of the bore provided in said knob, means provided on the inner end of said adapter to engage said bearing ring to hold the knob and adapter in assembled relatively rotatable engagement, said means comprising a self-threading screw, the outer end of said adapter being slotted longitudinally to provide resilient fingers to receive and grip the end of a lead pencil, and a locking sleeve to snugly enclose said resilient fingers to force said fingers into tight frictional engagement with a lead pencil.
